(57) **CLAIM**

The ornamental design for an attachment for hair dryers, as
shown and described.

DESCRIPTION

FIG. 1 is a perspective view of an attachment for hair dryers,
affixed to a hair dryer, showing our new design;

FIG. 2 is a front elevation thereof;

FIG. 3 is a side elevational view thereof, looking from the
right side of FIG. 2, the opposite side being a mirror image
thereof;

FIG. 4 is a rear elevational view thereof; and,

FIG. 5 is a top plan view thereof, the bottom plan view being
identical in appearance.

The broken lines showing a hair dryer in FIG. 1 are for
illustrative purposes only and do not form part of the
claimed design.
